OF LOWELL, MASSACHUSETTS, A CORPORATION OF MASSACHUSETTS

DESIGN FOR A BOTTLE

Application filed April 18, 1931. Serial No. 39,543. Term of patent 14 years.

To all whom it may concern:

Be it known that I, THOMAS S. HARRIS, a citizen of the United States, residing at Lowell, in the county of Middlesex and State of Massachusetts, have invented a new, original, and ornamental Design for a Bottle, as shown in the accompanying drawings, forming part of this specification.

In the drawings:

Fig. 1 is a perspective view of the bottle.
Fig. 2 is an expanded view of the side of

the bottle showing the design on the sides of the bottle.

The design consists in the novel and ornamental marking of the bottle having as a dominant feature the distinctive sun-burst design as illustrated in the drawings.

I claim:

The ornamental design for a bottle substantially as shown and described.

T. S. HARRIS.
